UNITED STATES PATENT OFFICE.

JOHN M. LEE, OF SPENCER, IOWA.

DETACHABLE-HANDLE CONSTRUCTION.

1,266,832.

Specification of Letters Patent. Patented May 21, 1918.

Application filed December 4, 1917. Serial No. 205,466.

To all whom it may concern:

Be it known that I, JOHN M. LEE, a citizen of the United States, and resident of Spencer, in the county of Clay and State of 5 Iowa, have invented a certain new and useful Detachable-Handle Construction, of which the following is a specification.

My invention relates to detachable handles for instruments, tools and the like. 10 The object of my invention is to provide a detachable handle and coacting instrument or tool member, such for instance as a surgeon's knife blade, the blade or the like and the handle having coacting parts whereby 15 the blade may be firmly and rigidly locked to the handle without the use of tools, or special instruments, which coacting parts permit the ready and easy separation of the handle and blade or the like.

More particularly it is my object to provide a handle having holding and locking pins or lugs thereon in connection with a blade or other instrument or tool having coacting, engaging parts such, for instance, as 20 openings of proper size and location to coact with said lugs or pins in connecting with a locking cover plate or the like adapted to be mounted on the handle and blade in such manner as to be firmly locked to the handle 25 and to firmly lock the blade to the handle.

With these and other objects in view my invention consists in the construction, arrangement and combination of the various parts of the device, whereby the objects contemplated are attained, as hereinafter more 30 fully set forth, pointed out in my claim and illustrated in the accompanying drawings, in which:

Figure 1 shows a plan view of a handle 40 and a knife blade embodying my invention.

Fig. 2 shows a front elevation of the same.

Fig. 3 shows an enlarged, detail view of a portion of the locking plate.

Fig. 4 shows a detail, sectional view taken 45 on the line 4—4 of Fig. 1.

Fig. 5 shows a detail, sectional view taken on the line 5—5 of Fig. 2; and

Fig. 6 shows an enlarged, plan view of a portion of the handle with the blade shank 50 thereon, the locking plate being omitted.

In the illustration of my invention shown in the accompanying drawings, I have used the reference numeral 10 to indicate generally the body of a handle forming part of my invention.

The handle 10 has at one end a portion 11 thinner than the body of the handle.

At the handle end of the portion 11 is a shoulder 12 beveled from its inner portion outwardly and toward the instrument end 60 of the device. The portion 11 has preferably near the shoulder 12 an upwardly extending pin 13 and another pin 14 preferably near its free end extending upwardly. The pin 14 is preferably larger than the pin 65 13 and has on opposite sides spaced from the portion 11 opposite flanges 15 extending transversely of the handle. The pin 13 and the main body of the pin 14 are cylindrical.

In Fig. 1 I have shown the handle resting on one side and I will for convenience sake call the lower edge of the handle, as shown in Fig. 1, its front edge.

The shoulder 12 extends from the rear to the front edge of the handle 10 and is preferably inclined from a transverse line, as illustrated in Figs. 1 and 6.

My improved handle may be used with a great variety of instruments and tools. For purposes of illustration I have shown the 80 handle used with a surgeon's knife blade 16 having a shank 17. The shank 17 has its free end inclined from a transverse line as at 18 and is formed with a hole 19 designed to receive the pin 13. The shank 17 is also 85 formed with a longitudinally, elongated slot 20, the width of which is such as to snugly receive the pin 14. The length of the slot 20 is such that when the shank is placed transversely across the portion 11, the slot 90 20 will receive the flanges 15 and the pin 14, permitting the shank to be slid down over the pin 14 until it rests on the portion 11. The shank 17 is of somewhat resilient material.

95 After having been slid over the pin 14 the shank may be rotated on said pin until the hole 19 is above the pin 13, whereupon the shank may be moved to position to fit snugly against the portion 11 with the pin 13 extending through the wall above the shank 17.

I provide a locking plate 21, having at one end a beveled edge 22, designed to coact with the shoulder 12 and inclined from a transverse line to fit the shoulder 12. It will thus 105 be seen that the beveled edge 22 and shoulder 12 form a dovetail. The locking plate has in its upper surface a counter-sunk recess 23.

Extending from the bottom of the recess 110

23 through the locking plate is a longitudinally, elongated slot 24.

On the under surface of the locking plate is a recess 25 designed to receive the end of the pin 13 which projects upwardly above the shank 17. The locking plate is of resilient material and the recess 25 is slightly enlarged as at 26 on the side thereof toward the rear edge of the handle when the parts 10 are installed.

In the practical assembling of the parts of my improved device and the mounting of the tool or the like on the handle for use, the handle is held substantially in the position shown in Fig. 1. The tool is grasped for instance by the blade 16 and placed on the portion 11 with the shank of the tool extending transversely across the portion 11 and with the slot 20 arranged to register 15 with the upper end of the pin 14. The shank is then dropped over the pin 13 and is rotated until the hole 19 registers with the pin 14. The shank is then moved to position resting upon the portion 11, whereupon the flanges 15 will overhang the body 25 of the shank and will be slightly spaced above the shank.

The locking plate 21 is then spaced above the shank 17, extending transversely across 30 it, with the slot 24 registering with the pin 14. The slot 24 is dropped over the pin 14 and the locking plate is then rotated until the flanges 15 overhang and snugly engage the counter-sunk portion of the plate 21 adjacent to the slot 24.

The plate 21 is sprung over the pin 13 until the recess 25 registers with the upwardly projecting part of the pin 13 and at the same time the beveled edge 22 is beneath 40 and interlocked with the edge of the shoulder 12.

It will be seen that the shoulder 12 and beveled edge 22 are inclined from the transverse line in order to permit these parts to 45 swing together properly.

I have found that by forming the recess 25 with the extension 26, as described and illustrated, it is much easier to start the

locking plate 21 in beginning the disassembling of the parts.

In order to further facilitate the disassembling of the parts, the forward edge of the locking plate 21 is preferably provided with a slight recess for the finger nail.

The relative arrangement of the pin 13, 55 the recess 25, the beveled edge 22 and shoulder 12 are such that when the parts are assembled they are firmly and yieldingly held in locked position.

The advantages of such a device as is 60 herein described may be largely seen from the foregoing description.

It is obvious that with my improved handle, locking plate and shank a great variety of tools and instruments may be employed, such, for instance, as surgeons' instruments, dentists' instruments and the like. 65

It is not my intention to confine my invention to use with surgeons' knives, or any one class of instruments or tools.

It will be obvious that the sizes and proportions as well as the materials of the parts may be varied as may be desired for a great variety of purposes, and it is my intention to cover by my claim any modified forms of 75 structure or use of mechanical equivalents which may be included within their scope.

I claim as my invention:

In a device of the class described, the combination of a handle having at one end a 80 portion with a beveled shoulder, said portion having a projecting pin and having spaced therefrom a projecting pin having spaced from said portion, opposite laterally, extending flanges, an instrument or tool member having a shank provided with a hole to receive said first pin and with an elongated slot to receive said second pin, a resilient locking plate having an elongated slot to receive said second pin, and a recess 85 to receive the head of said first pin and having one edge adapted to be under the edge of said beveled shoulder when said last described slot and said recess receive said pins.

Des Moines, Iowa, November 24, 1917.

JOHN M. LEE.
